(57) **CLAIM**

The ornamental design for a pump for inflating tyres as shown and described.

DESCRIPTION

The patent or application file contains at least one drawing executed in color. Copies of this patent or patent application publication with color drawing(s) will be provided by the Office upon request and payment of the necessary fee.

1. Pump for inflating tyres

1.1 is a front, right and top side perspective view of a pump for inflating tyres showing my new design;

1.2 is a front elevational view thereof;

1.3 is a rear elevational view thereof;

1.4 is a left side elevational view thereof;

1.5 is a right side elevational view thereof;

1.6 is a top plan view thereof; and

1.7 is a bottom plan view thereof.

Colors form no part of the claimed design.

The portions of the article shown by red coloring form no part of the claimed design.

1 Claim, 7 Drawing Sheets
(7 of 7 Drawing Sheet(s) Filed in Color)
